UNITED STATES PATENT OFFICE.

LE ROY FRANK JOHNSON, OF WILLMAR, MINNESOTA.

DOOR-CLOSING DEVICE FOR BOX CARS.

Application filed October 29, 1926. Serial No. 144,973.

This invention relates to a door closing device for railway cars such as the box cars now commonly used for shipping grain. A difficulty is often experienced in getting the car doors into closed position. It has thus become a common practice for the railway operatives to take a crowbar, or wrecking bar and pry the door shut by engaging its rear side. This practice results in the side of a car becoming greatly damaged by the continual jabbing therewith of the wrecking bar, or crowbar. The repair bill for such damaged cars is a large and regular item.

It is the object of this invention, therefore, to provide a simple, inexpensive, easily operated and efficient device for closing the car doors without damaging the car.

It is the further object of the invention to provide a door closing device comprising a bar adapted to engage the car structure at one end and having a member swingably connected thereto adjacent said end for engaging the car door and moving the same to closed position.

These and other objects and advantages of the invention will be fully set forth in the following description made in connection with the accompanying drawings in which like reference characters refer to the same parts throughout the different views and in which,

Fig. 1, is a view in horizontal cross section of a portion of a box car showing the device in side elevation as used therewith, different positions of the device being shown in dotted lines.

Fig. 2 is a view in side elevation of the device,

Fig. 3 is a partial edge view of the device, and

Fig. 4 is a vertical section taken on line 4—4 of Fig. 2, as indicated by the arrows.

Referring to the drawings, a portion of a car structure is shown including the door post 10 from one side of which extend the side portions 11 of the car, said portions being shown as rabbeted into post 10. A door plate 12 is shown as secured to the outer side of post 10 and keepers 13 will be vertically spaced along the side 11 which keepers are adapted to extend over the edge of the door 14 when in closed position. An inner door 15 is commonly used, particularly on grain carrying cars, which door is of a temporary nature and made from wooden boards.

In accordance with the present invention

the bar 16 is provided and while this bar may be variously shaped in the embodiment of the invention illustrated, the same is shown as octagonal in cross section. Said bar 16 is pointed at one end 16^a and a short distance from said end has connected thereto a swingable link 17. The link 17 preferably has a hook portion 17^a at its free end. Said link is shown as having a slotted or looped portion 17^b adjacent its other end embracing the bar 16. The member 17 is movable longitudinally of bar 16 and limited in movement thereon by a bail or keeper 16^c. While the keeper 16^c may be variously formed and connected to bar 16, in the embodiment of the invention illustrated it is shown as having its end portions 16^c extending around bar 16 and welded together. The outer end of the bar 16 is formed with a substantially semi-circular hook 16^d, the terminal end 16^e of which is flattened to form a chisel edge.

In operation when the door 14 is to be closed, the device will be positioned as shown in full lines in Fig. 1. Point 16^a will be engaged in the inner door 15 and the hook end 17^a of member 17 will be engaged in the door keeper 14^a. The outer end of bar 16 will now be swung to the left as shown in Fig. 1 and door 14 will be drawn toward closed position. The bar 16 may be repeatedly engaged in the door 15 in moving door 14 and when door 14 is almost closed the end of bar 16 will be engaged at the outer edge of door plate 12 as shown in dotted lines in Fig. 1 and the same swung to the left into the position shown at the extreme left of Fig. 1. The door is thus brought to a closed position without in any way mutilating or marring the sides of the car. It is immaterial if the point of bar 16 is jabbed into the inner or grain door 15, as this door is usually destroyed when the car is unloaded. The hook 16^d on the device forms a convenient handle for carrying the same and this hook can be engaged over one arm of the operator when the device is carried. The keeper 16^c is provided and link 17 permitted to move along bar 16 to accommodate different types of cars. In some cars the inner door 15 is farther in the rear of the outer door 14. The edge 16^e of the bar can be used for nail pulling and wrecking purposes.

From the above description it is seen that applicant has provided a very simple and

efficient door closing device. The same can be easily and inexpensively produced and at the same time made very durable. The device has been amply demonstrated in actual practice and found to be very successful and efficient, and the device is now being used in considerable numbers by at least one railway company.

It will, of course, be understood that various changes may be made in the form, details, arrangement and proportions of the device without departing from the scope of applicant's invention, which generally stated consists of a device capable of carrying out the objects above set forth, such as shown and described and defined in the appended claims.

What I claim is:

1. A device for closing car doors, comprising a comparatively long narrow bar formed with a point at one end so as to be stuck into the side of the box car or to engage a ledge at the side of said car, a loop formed on said bar adjacent one end, a link

having a hook at its free end slidably embracing said bar at its other end within said loop whereby a door may be engaged by said hook and moved to closed position by said bar acting as a lever. 25

2. A device for closing car doors comprising a bar having a pointed end adapted to engage the car structure, a hook link permanently and swingably connected to said bar adjacent said end movable longitudinally of said bar and adapted to hook into the door structure whereby said bar may be swung as a lever and said link will pull said door toward closed position. 30

3. A device for closing car doors comprising a bar pointed at one end and having a loop thereon adjacent said end, a link having a slot adjacent one end embracing said bar disposed within and retained thereon by said loop, said link having a hook at one end and said bar having a handle at its other end by 35 which it may be carried. 40

In testimony whereof I affix my signature.
LE ROY FRANK JOHNSON. 45
